UNITED STATES PATENT OFFICE.

EMILE TINTANNÉ, OF CAMAGUEY, CUBA.

SCRIBER.

1,301,621.

Specification of Letters Patent. Patented Apr. 22, 1919.

Application filed June 5, 1918. Serial No. 238,324.

To all whom it may concern:

Be it known that I, EMILE TINTANNÉ, a citizen of the United States, residing at Camaguey, in the Province of Camaguey 5 and Republic of Cuba, have invented certain new and useful Improvements in Scribes, of which the following is a specification, reference being had to the accompanying drawings.

10 This invention relates to certain improvements in scribes and it is an object of the invention to provide a device of this general character having novel and improved means whereby the same may be employed to produce a curved line of varying radius.

15 The invention also has for an object to provide an instrument of this general character including a main or supporting leg together with a marking implement yieldably supported by the leg or supporting member whereby said marking implement is movable relative to the supporting leg or member so that the marking implement may readily follow a guiding edge.

20 25 Another object of the invention is to provide a novel and improved instrument of this general character which includes a supporting leg or member yieldingly supporting a marking implement and wherein a guide member coacts with the marking implement for controlling the working movement of the implement together with means for relatively adjusting the guiding member and the marking implement.

30 35 Furthermore, it is an object of the invention to provide a novel and improved instrument of this general character including a supporting leg or member having yieldably connected thereto a sleeve with which a marking implement is supported and wherein said marking implement is capable of lateral and longitudinal movement independently of the sleeve together with means coacting with the implement for constantly urging the same in a direction away from the work.

40 45 The invention consists in the details of construction and in the combination and arrangement of the several parts of my improved scribe whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be the better understood, I will now proceed to describe the same with reference to the accompanying drawings, wherein:

Figure 1 is a view in side elevation of a scribe constructed in accordance with an embodiment of my invention;

Fig. 2 is a fragmentary view partly in 65 longitudinal section and partly in elevation illustrating certain features of the invention as herein disclosed;

Fig. 3 is a sectional view taken substantially on the line 3—3 of Fig. 1; 70

Fig. 4 is an enlarged fragmentary sectional view illustrating the means for adjusting the marking implement relative to the guide member;

Fig. 5 is a fragmentary view in elevation 75 with a part in section of the marking implement and the adjusting member coacting therewith;

Fig. 6 is a fragmentary view in elevation of the working end portion of the guide 80 member; and

Fig. 7 is a fragmentary view in plan of a guide with which my improved scribe may be employed.

As disclosed in the accompanying drawings L denotes a supporting leg or member having engaged with the working end thereof in a conventional manner the needle N. The opposite end portion of the leg or member L is fluted or otherwise roughened 85 as at 1 to facilitate the manipulation of the instrument. S denotes a sleeve of predetermined dimensions arranged at one side of the leg or member L and the inner or upper end portion of said sleeve is connected with 90 the upper end portion of the leg or member L through the medium of the flat spring 2 possessing the greatest degree of flexibility at the portion a immediately adjacent the connection between the spring 2 and the leg 100 L. The spring 2 serves to constantly urge the sleeve S in a direction away from the supporting leg or member L. The lower or outer end portion of the sleeve S has pivotally engaged therewith as at 3 the end portion of the flexible member or spring 4 which is disposed through a suitable opening 5 in the leg or member L adjacent the needle N and coacting with the spring 4 is 105 the screw 6 in threaded engagement with the 110

leg or member L and adapted to frictionally engage the spring 4. The screw 6 and the spring 4 coact to prevent an abrupt upward or jumping movement of the sleeve S and more particularly the marking implement (to be hereinafter more particularly referred to) when the marking implement is free from the work.

As herein illustrated the marking implement M comprises a bow pen of a conventional type detachably engaged within a head or socket 8 provided at the lower end portion of the cylindrical stem 9. It is to be understood that I do not wish to limit myself to any particular type of marking implement as the same may be a pencil or other marking or writing medium.

The stem 9 is of a length in excess of the length of the sleeve S and is slidably disposed through the sleeve and the shoulder 10 afforded by the head or socket 8 normally contacts with the lower or outer end portion of the sleeve S.

Engaged with the upper or outer end portion of the stem 9 is a headed member 11 and secured to the peripheral portion of the head of said member is an extremity of a coil spring 12. The spring 12 encircles the portion of the stem above the sleeve S and has its opposite end portion anchored to the inner or upper end portion of said sleeve. This spring constantly urges the stem 9 inwardly or upwardly yet permits sufficient rotation of the stem within the sleeve to meet the requirements of practice.

T denotes a trace or guide member formed of resilient material and having one end suitably anchored to the outer face of the head or socket 8. In the present embodiment of my invention an end portion of the trace or guide member T is inserted within a supplemental socket or recess in the head 8 and engaging said end portion of the trace or guide member T is a clamping screw 8' or the like in threaded engagement with the head 8. The member adjacent the socket is bent upwardly and downwardly to afford a loop to increase the spring action of this member and the free end portion of the member is substantially straight and is positioned in close proximity to the outer face of the marking implement M. The free extremity of the member T normally extends beyond the working end of the implement M so that in setting the instrument the marking implement is out of contact with the work. When it is desired to produce or inscribe a line it is only necessary for the operator to press downwardly upon the stem 9 and which pressure may be partly obtained by one of the digits of the hand engaged with the supporting leg or member L. As soon as the stem 9 is relieved of this pressure the spring 12 immediately returns the implement M to its normal position. The free

end portion of the member T is provided with the lateral extension 15 which is adapted to afford an increased surface for contact with the working edge of the guide G. The guide G is preferably of the type particularly described and illustrated in my co-pending application executed on even date herewith Serial No. 238,325. The working edge of said guide as herein illustrated is a wall produced by an opening in the plate 75 preferably of transparent xylonite or other transparent material.

In use the needle N is fixed at approximately the center of the opening O in the guide G with the lower or working end of 80 the member T in contact with the edge defining said opening. Pressure is then applied to the stem 9 to bring the marking implement M in contact with the paper. Upon turning movement of the leg or member L 85 the implement M will produce upon the paper or other surface worked upon a line concentric to the edge of the opening O. In view of this it will be at once understood that my improved scribe is of especial advantage in the production of a line arranged on a curve of varying radius such as is required in the forming of script lettering generally employed in connection with geometrical design. The production of a line of this character is facilitated by the relative movement 90 between the sleeve S and the leg or member L and the longitudinal and rotatable movement of the stem 9 relative to the sleeve S.

The upper or inner end portion of the 100 straight portion 14 of the member T has secured to the front face thereof a block 16 and which block is preferably held in position by solder, although I do not wish to be understood as limiting myself in this respect. Threaded through the block 16 is a headed shank 17 and the free end portion 18 of said shank 17 has its periphery smooth as particularly illustrated in Fig. 4, and the portion 18 is disposed through the slot or 110 slots 19 produced in the marking implement M. Threaded upon the shank 17 adjacent the portion 18 thereof is a nut or head 20 which contacts with the marking implement M so that upon endwise movement of 115 the shank 17 the implement M may be spaced relative to the part 14 of the member D as the occasions of practice may require in order to produce lines concentric to the guiding edge as afforded by the opening O in the 120 guide G but of different axes.

It is of importance that the part 14 of the guide member T be substantially rigid and it is also of importance to provide the lower portion of the part 14 with a small 125 bearing member or block 21 which assures at all times a slight separation between the part 14 of the member T and the marking implement M.

From the foregoing description it is 130

thought to be obvious that a scribe constructed in accordance with my invention is particularly well adapted for use by reason of the convenience and facility with which it may be assembled and operated and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

15 I claim:

1. A scribe consisting of a supporting leg, a marking implement, a resilient member connecting the marking implement and the leg, said resilient member urging the marking implement in a direction away from the leg, a flexible member operatively engaged with the marking implement, and means carried by the leg for frictionally engaging the flexible member.
- 25 2. A scribe comprising a supporting leg, a sleeve positioned at one side thereof, a resilient connection between the sleeve and the leg, said leg and sleeve being otherwise free one from the other, a marking implement engaged with the sleeve and capable of movement longitudinally of the sleeve, and means for constantly urging the marking implement in one direction longitudinally of the sleeve, said marking implement at all 35 times being also capable of rotary movement.
3. A scribe consisting of a leg, a marking implement yieldingly supported by said leg, a guide member carried by the marking implement and coacting with the working end thereof, and means for normally maintaining the working end of the marking implement spaced from the working end of the guide member.

4. A scribe consisting of a leg, a marking implement yieldingly supported by said leg, said implement being provided with a slot, a guide member carried by the marking implement and coacting with the working end thereof, and a member carried by the guide member and extending into the slot of the marking implement.

5. A scribe consisting of a leg, a marking implement yieldingly supported by said leg, a guide member carried by the marking implement and coacting with the working end thereof, a portion of the guide member being looped to increase the resiliency thereof.

6. A scribe consisting of a leg, a marking implement yieldingly supported by said leg, a guide member carried by the marking implement and coacting with the working end thereof, the working end portion of the guide member having a block secured to a face thereof to prevent contact of the working end of the marking implement with the working end of the guiding member.

7. A scribe consisting of a leg, a marking implement yieldingly supported by said leg, said implement being provided with a slot, a guide member carried by the marking implement and coacting with the working end thereof, and a member carried by the guide member and extending into the slot of the marking implement, said last named member being endwise adjustable, and means carried by said last named member for contact with the marking implement whereby said marking implement and guide member may be relatively adjusted.

In testimony whereof I hereunto affix my signature in the presence of two witnesses.

EMILE TINTANNÉ.
